UNITED STATES PATENT OFFICE.

MARCO RIGHETTO AND CARLO ZORZI, OF MILAN, ITALY.

CONCRETE RAILWAY TIE.

Application filed January 18, 1923. Serial No. 613,496.

To all whom it may concern:

Be it known that we, MARCO RIGHETTO and CARLO ZORZI, subjects of the King of Italy, residing at Milan, Italy, have invented 5 certain new and useful Improvements in Concrete Railway Ties, of which the following is a specification.

The present invention relates to concrete rail ties and fasteners; and it comprises, 10 briefly, an improved construction embodying a hollow ferro-concrete tie possessing the elasticity and solidity necessary to resist both mechanical and atmospheric forces, and a rail fastener attachable to the tie 15 without the latter being drilled or being cut away or otherwise changed as to its cross-sectional area, thereby avoiding weakening.

According to the invention, the tie is 20 moulded under the action of centrifugal force, which renders the walls thus produced extremely homogeneous and resist- 25 ant, and which results in the formation of a substantially-cylindrical central bore or opening. The reinforcements embedded in the tie are preferably disposed parallel with the axis of the tie and in correspondence with its exterior contour so that they 30 form a cage or ring which encloses the bore. Finally, the rail plates are fastened to the tie by means of stirrup or U-bolts which 35 straddle the tie and extend through perforations in the plates, their projecting ends carrying clips for engagement with the rail flanges. Other and further improved fea- 40 tures are also involved in the invention, and will be set forth in the description which follows.

The accompanying drawing shows various 45 forms which the invention may take in practice, and therein:

Figure 1 is a side view of one form;

Fig. 2 is a cross-section thereof;

Fig. 3 is a cross-section of a modifica- 50 tion;

Fig. 4 is a bottom plan view showing a single diagonally-arranged stirrup bolt; and

Fig. 5 is a bottom plan view showing the 55 use of pairs of stirrup bolts, such arrangement being preferably adopted at the points where the rails are jointed together.

Referring more particularly to the drawing, 1 indicates the reinforced concrete tie 55 which, as previously explained, is moulded by the action of centrifugal force; such op-

eration producing an element somewhat in the nature of a pipe and having a cylindrical axial bore 2. The tie may have any desired cross-sectional shape: thus, it is shown 60 in Fig. 2 as having a curved or semi-circular upper part and a rectangular lower part; and in Fig. 3 as triangular, all of the angles or corners being rounded. The internal reinforcements extend parallel with the 65 axis of the tie and are preferably disposed in a manner to conform to the cross-sectional shape of the tie, so that they form a longitudinal cage or ring, as will be understood from Figs. 2 and 3.

The rail fastener consists of a stirrup or U-bolt 3, which is arranged to straddle the tie from the under side thereof, so that its arms project upwardly across and beyond the opposite side faces of the tie. The free 70 ends of the bolt arms extend through openings formed in a rail plate 4 and carry clips 5 which are adapted to engage the flanges of the rails 7 and are held in place by nuts 6 threaded on the said arm ends. A cushion- 75 plate or strip 8 of elastic material is preferably interposed between the rail plate 4 and the top face of the tie, and one or more projections 9 may be provided on the tie to engage the adjacent end of the rail 80 plate and thereby hold the latter and the stirrup bolt against sliding movement along the tie.

Ordinarily, a single stirrup bolt only is used with each rail plate 4, and in such case 85 said bolt is arranged diagonally, as clearly shown in Fig. 4. Adjacent the points where the joints between successive rails occur, however, it is preferable to use two bolts 90 with each rail plate and to dispose them at 95 opposite sides of the rail and perpendicular to the tie, as illustrated in Fig. 5. In either case, the ends of the bolt arms pass through vertical openings formed in the rail plate, the precise shape of the plate depending 100 upon the cross-sectional shape of the upper part of the tie. Where the latter has a curved or angular top part (Figs. 2 and 3), the under face of the plate is provided with a seat wherein the tie part 105 conformably fits. This seat may, as shown, be formed conjointly by a pair of depending angular shoulders produced by thickening the plate and disposed in spaced relation to each other.

We claim as our invention:

1. The combination, with a concrete tie

having a transversely curved upper surface, of a rail plate mounted on said curved surface and having its under face provided with a pair of depending angular shoulders 5 which are spaced apart to conjointly form between them a seat adapted to conformably receive the said curved surface, one or more stirrup bolts for fastening the tie and rail plate together; said bolts having their arms 10 disposed exteriorly of the tie and projecting upwardly through openings in said plate, and clips carried by the ends of said bolt arms for engagement with a rail; substantially as described.

15 2. The combination, with a concrete tie having a transversely curved upper surface, of a rail plate mounted on said curved surface and having its under face provided

with a pair of depending angular shoulders which are spaced apart to conjointly form 20 between them a seat adapted to conformably receive the said curved surface, an elastic cushion interposed between the rail plate and the upper surface of the tie, one or more stirrup bolts for fastening the tie and 25 rail plate together; said bolts having their arms disposed exteriorly of the tie and projecting upwardly through openings in said plate, and clips carried by the ends of said bolt arms for engagement with a rail; substantially as described.

In testimony whereof we affix our signatures.

MARCO RIGHETTO.
CARLO ZORZI.
